LABELING APPARATUS

Louis Mandel, Newark, N. J., assignor to The Slick-Shine Co., Inc., Newark, N. J., a corporation of New Jersey

Application January 14, 1939, Serial No. 250,895

9 Claims. (Cl. 216—42)

The invention relates to labeling apparatus and more particularly to apparatus for use in the manual application of labels to the articles for which said labels are designed.

5 The object of the invention is to provide an apparatus of the indicated type whereby the labels may be efficiently applied to the articles in a simple and efficient manner and so as to locate successive labels in predetermined uniform positions on successive articles. The invention contemplates further an apparatus which may be utilized in connection with articles of varying surface contour and with labels of different designs and shapes, and which requires no particular skill in its operation.

Other more specific objects will appear from the description hereinafter and the features of novelty will be pointed out in the claims.

In the accompanying drawings, which illustrate examples of the invention without defining its limits, Fig. 1 is a plan view of the novel apparatus in one form; Fig. 2 is a sectional elevation thereof on the line 2—2 of Fig. 1; Fig. 3 is a perspective view of a bearing bracket included in the apparatus; Fig. 4 is an enlarged detail sectional view of a locking means embodied therein; Fig. 5 is a plan view of another form of the apparatus; Fig. 6 is a cross-section on the line 6—6 of Fig. 5; Fig. 7 is a detail perspective view of a label positioning element included in the apparatus; Figs. 8 and 9 are perspective views respectively of two different forms of moistening devices; Fig. 10 is a plan view of still another form of the apparatus; Fig. 11 is a longitudinal section on the line 11—11 of Fig. 10; and Figs. 12 and 13 are fragmentary perspective views of the holders for the articles to be labeled.

In its general construction, the apparatus comprises a base 15 preferably carried by suitable supporting legs 16 and itself serving as a support for a table or top 17 located at a distance above and in vertical registry with the base 15. The table or top 17 is maintained in place by means 40 of corner bolts 18 which pass through spacing sleeves 19 located between and in engagement with said base 15 and the table or top 17 and serving as supports for the latter as shown in Fig. 2. The table or top 17 is provided with 45 groups of slots 20 and 21, extending in directions which radiate outwardly from the central point of said table or top 17 as illustrated in Fig. 1; the slots 20 extend in aligned pairs in directions at right angles to each other longitudinally and 50 transversely of said table 17, while the slots 21

are arranged in corresponding aligned pairs in inclined relation to the slots 20 as shown in Fig. 1. The slots 20 and 21 are formed with shoulders 22 along opposite edges and at least one end thereof for the purpose to be more fully set forth 5 hereinafter.

The apparatus further includes means for positioning a supply stack of labels 23 upon the table or top 17 and for maintaining said stack in place thereon during the labeling operations. 10 The label positioning means is shown in the form of guide members or pins 24 projecting upwardly through the slots 20 and 21 to define a label enclosure on the upper face of the table or top 17. In order to accommodate labels 23 of varying 15 dimensions and different contours or shape and to permit the position of the label enclosure and consequently the location of the stack of labels 23 on the table or top 17 to be varied at will, the guide members or pins 24 are so arranged that the position thereof in said slots 20 and 21 may be selectively adjusted as required. For this purpose each guide pin or rod 24 is carried by a bearing bracket 25 arranged in surface engagement with the lower face of the table 17 20 in registry with one of the slots 20 or 21. The brackets 25 are connected by means of bolts 26 and nuts 27 with co-operating plates or slides 28 resting upon the shoulders 22 of the slots 20 and 21 and slidably fitting the latter, washers 29 25 being located on the bolts 26 in engagement with the lower surfaces of said brackets 25 to provide bearing surfaces for the associated nuts 27. To increase the range of adjustability of the guide pins or rods 24, the brackets 25 may be formed 30 with slots 30 for the accommodation of the bolts 26 as shown in Figs. 2 and 3. The heads of the bolts 26 do not project above the table or top 17 and preferably are flush with the upper surface thereof as shown in Fig. 2, so as not to interfere with the adjustment of other elements of the apparatus on said table or top 17.

40 In the operation of applying the labels 23 to the articles A for which said labels are designed, the guide pins 24 act as supports for said articles A and are compressible thereby to enable the supported article A to be brought into contact with the current terminal label 23 at the top of the supply stack. For this purpose the brackets 25 include depending bosses 31 in which the 45 guide pins 24 are slidably mounted for vertical movement therein; to permit the downward movements of said guide pins 24 without interference, regardless of the positions occupied by the brackets 25, the base 15 is preferably pro- 50 55

vided with slots 32 in vertical registry with the slots 20 and 21 of the table or top 17. In the preferred arrangement, the guide pins 24 are controlled by springs 33 which bear with one 5 end against the base 15 and with the other end engage projections on the pins or rods 24 as exemplified by the cotter pins 34; the latter, by contact with the lower ends of the bosses 31 serve also to arrest the upward movements of the pins 10 or rods 24 under the influence of the springs 33.

In addition to the parts so far described, the apparatus includes means for positioning the articles A in predetermined relation to the supply stack of labels 23 and for controlling the movements of the articles A in such predetermined relation to said stack to thereby definitely predetermine the location of successive labels 23 on successive articles A. For illustrative and descriptive purposes and without intent to define 15 the operative limits of the apparatus, the articles A are exemplified by bottles, and the aforesaid positioning means is shown in a form arranged to co-operate therewith, and comprising a plurality of carriers 35 provided with slots 36 extending lengthwise thereof. The carriers 35 constitute supports for upright members 37 preferably having relatively bevelled vertical edges 38 as shown in Fig. 1. The carriers 35 are located in surface engagement with the upper face of 20 the table or top 17 and are selectively adjustable thereon to locate the upright members 37 in a manner to properly define the label receiving position of the bottles A or equivalent articles. In the illustrated example, the carriers 35 are 25 controlled by bolts 39 projecting through the slots 36 and having preferably squared sections 40 slidably fitted in the slots 21 and heads 41 in engagement with the lower face of the table or top 17; with this arrangement the squared sections 40 in conjunction with the slots 21 maintain the bolts 39 against rotation on their axes. Washers 42 are mounted on the bolts 39 in contact with the carriers 35 for clamping engagement by nuts 43 threaded on the bolts 39 as 30 illustrated in Fig. 4.

In utilizing the apparatus shown in Figs. 1 and 2, the bearing brackets 25 are shifted in directions to move the guide pins 24 lengthwise of the slots 20 and 21; the various pins 24 are adjusted 35 relatively to each other to define an enclosure for the particular labels 23 arranged in a supply stack and for locating said stack of labels 23 at a predetermined point of the top or table 17. The brackets 25 may be clamped in place by tightening 40 of the nuts 27 on the bolts 26 to thereby fix the guide pins 24 in position in the slots 20 and 21; the stack of labels 23 may then be placed in an upright position in the enclosure defined by said rods 24. Either at this stage or previously, 45 the carriers 35 are manipulated to set one pair of upright members 37 in spaced parallel relation to each other, and to set another pair of said upright members 37 in converging directions with the bevelled edges 38 in spaced parallel relation 50 to each other as shown in Fig. 1. In the illustrated example, the distance between the opposite parallel members 37 corresponds to the outside transverse dimensions of the bodies of the bottles A to which the labels 23 are to be applied, 55 while the distance between the bevelled edges 38 of the converging members 37 corresponds to the outside diameters of the necks of said bottles A. The adjustment of the converging members 37 is furthermore such that the bevelled edges 38 60 thereof provide abutments for the beads a

customarily found on the necks of conventional bottles to thereby position the bodies of the bottles A in predetermined relation to the supply stack of labels 23.

In practice, if a stack of gummed labels 23 is used, the outer surface of the bottles A which is to receive the label is first moistened or dampened in any convenient manner; if the labels 23 in the supply stack are not gummed, a coating of adhesive is suitably applied to the outer surface of the bottle A. In any case the bottle A, either previously moistened or coated with adhesive, is placed upon the upper ends of the guide members or pins 24 with the moistened or adhesive coated surface facing downwardly and with the body of said bottle A between the parallel upright members 37, and the neck thereof between the bevelled edges 38 of the converging upright members 37 with the bead a in contact with said bevelled edges 38 as shown by dotted lines in Fig. 20 1. At this stage the bottle A accordingly is supported by the pins 24 with the body of said bottle above and in predetermined relation to the terminal label 23 at the upper end of the supply stack.

With the bottle A thus supported and positioned, a downward pressure is manually exerted thereon which depresses the pins 24 in the bosses 31 against the tension of the springs 33 and thereby brings the moistened or gummed surface of said bottle A into surface engagement with the terminal label 23 which is at the top of the supply stack at the time. Subsequent to such contact, sufficient pressure is exerted on the bottle A to cause said terminal label 23 to adhere thereto after which said bottle A and attached label 23 is lifted from the apparatus; as this takes place, the springs 33 will restore the guide pins 24 to normal positions ready to receive and support the next bottle A to be labeled.

It will be noted that the spaced, parallel upright members 37 extend lengthwise of the bottle A and thus provide guide surfaces for the latter in its vertical movements to pick up and remove a terminal label 23 from the supply stack; 45 at the same time, these members 37 guide the bottle A in any lengthwise adjustment which may be required to bring the bead a into contact with the bevelled edges 38 of the converging upright members 37. Successive bottles A may accordingly be speedily placed in accurate label receiving position in the apparatus and labeled without requiring any special skill or time consuming effort or care on the part of the operator.

The apparatus shown in Figs. 5 and 6 corresponds essentially to the one illustrated in Figs. 1 and 2, and differs therefrom only in the character and operation of the means whereby a supply stack of labels 23^a is positioned upon the table or top 17. In the illustrated example, the 55 positioning means includes guide members or pins 24^a corresponding to the guide members or pins 24 of the form first described, and similarly mounted for adjustment lengthwise of the two aligning slots 20 which extend longitudinally 60 of the table or top 17. In addition to the guide pins 24^a the positioning means includes guide members in the form of upright plates 44 preferably flaring outwardly in opposite directions at their upper ends for instance by being curved as 65 illustrated at 45 in Figs. 6 and 7. The plates 44 are carried by members 46 pivotally attached at 47 to brackets 25^a, springs 48 being provided for exerting resilient forces upon said members 46 and the plates 44 carried thereby for the pur- 75

pose to be more fully set forth hereinafter. The brackets 25^a are adapted to rest upon the table or top 17 and are provided with slots 30^a arranged to register with the transverse slots 20 of said top or table 17. Bolts 26^a project through the slots 30^a and 20, and in co-operation with plates 28^a, washers 29^a and nuts 27^a, serve to fix said brackets 25^a in adjusted positions on said top or table 17 to thereby locate the plates 44 at predetermined points thereon for co-operation with the aforesaid guide pins 24^a in defining an enclosure for the supply stack of labels 23^a.

In practice the guide members or pins 24^a are adjusted lengthwise of the longitudinal slots 20 and the guide members or plates 44 along the transverse slots 20 and fixed in place, in the same way as described with respect to Figs. 1 and 2 to locate the supply stack of labels 23^a at a predetermined point on the table 17. The form of apparatus illustrated in Figs. 5 and 6 is designed primarily for applying labels to articles of other than rectangular cross-section as for instance bottles A' having cylindrical bodies, and necks provided with conventional annular beads a' as shown by dotted lines in Figs. 5 and 6. In describing the operation of the apparatus it will be assumed that the labels 23^a are gummed although it is to be understood that the apparatus may be used equally well with ungummed labels, in which case the surface of the bottle A' instead of being moistened to pick up the gummed label 23^a will be coated with adhesive to correspondingly pick up an ungummed label.

To apply a gummed label 23^a to a cylindrical bottle A', the latter, with its surface previously moistened, is placed between the parallel upright members 37 and the converging upright members 37 with the bead a' in engagement with the bevelled edges 38 of the latter and with the body of said bottle A' resting upon the guide pins 24^a as shown by broken lines in Fig. 6 in the same way as in the form first described. A downward pressure is then manually exerted on the bottle A' to depress the guide members or pins 24^a and thereby bring the body of the bottle A' into engagement with the outwardly flaring or curved ends 45 of the guide members or plates 44. If the supply stack of labels 23^a is sufficiently high as illustrated in Fig. 6, the bottle A' at this stage will engage the terminal label 23^a at the upper end of said stack, with said label in tangential relation to the body of the bottle A'. If previous removals of successive terminal labels 23^a has reduced the height of the supply stack, or for some other reason the current terminal label 23^a thereof is at a lower level so as not to be contacted by the bottle A' when the latter initially engages the curved ends 45 of said plates 44, the aforesaid downward pressure on said bottle A' is continued. This will develop a camming action on said curved ends 45 whereby the plates 44 will be pivotally spread apart against the tension of the springs 48 to enable the bottle A' to engage the terminal label 23^a as indicated also by broken lines in Fig. 6. In all other respects the apparatus shown in Figs. 5 and 6 may be constructed and operate in the same way as the one illustrated in Figs. 1 and 2.

In any case, regardless of the height of the supply stack, the terminal label 23^a at the top thereof will engage the bottle A' in tangential relation thereto and will adhere thereto as the bottle A' is removed from the apparatus. The application of the label 23^a to said bottle A' may then be completed in any suitable manner and

the operations repeated with the next successive bottle to be labeled.

While the application of liquid to the bottles A and A' or equivalent articles, to moisten the surfaces thereof or to coat the same with adhesive, may be accomplished in any convenient manner, these operations may be advantageously carried out by means of devices such as illustrated in Figs. 8 and 9. The latter are shown in a form adapted to moisten the surfaces of the bottles A or A', or equivalent articles, and will be so described; the devices may be used with equal efficiency for applying adhesive to said bottles or other articles as will be apparent from the description hereinafter.

In the illustrated form both devices include a base 49 and spaced upright supports 50 secured thereon in any convenient manner as by means of screws 51 or the like, which pass through flanges 52 located at the lower ends of said supports 50. The latter, as shown, are further provided at their upper ends with outwardly projecting flanges 53 constituting rests for channelled members 54 and 54^a respectively. The members 54 and 54^a are provided with flanges 55 which depend therefrom over the free edges of the flanges 53 and serve to position the channelled members 54 and 54^a between the supports 50 of the respective devices; in addition the members 54 and 54^a respectively carry layers 56 and 56^a of suitable material such as felt or the like, which layers preferably extend over the tops of the supports 50 and downwardly in surface engagement with the depending flanges 55 as shown. In the preferred arrangement angle bars 57 are fitted over the opposite edge portions of the layers 56 and 56^a and secured in place by screws 58 to fasten the respective parts in position on the supports 50.

The layers 56 and 56^a may be kept in a moistened condition or supplied with adhesive in any convenient manner. For instance, water may be supplied thereto by capillary attraction through the medium of wicks 59 which are immersed in water contained in receptacles 60 mounted on the bases 49 beneath the channelled members 50 and 54^a. The device shown in Fig. 8 is designed for cylindrical bottles and the like for which reason the channel member 54 is of curved form and the layer 56 is correspondingly of curved form to provide a curved recess or trough; in Fig. 9 the channel member 54^a is of rectangular form and the layer 56^a is similarly shaped to provide a rectangular recess or trough.

In using the device of Fig. 8, the article such as for instance the bottle A' is placed in the curved trough in contact with the layer 56 which accordingly moistens the surface of said bottle A' or its equivalent, to receive the label 23^a as hereinbefore described; the device of Fig. 9 is similarly used for moistening the surfaces of articles of rectangular form such as the bottle A.

Devices corresponding in construction shown in Figs. 8 and 9 but omitting the wicks 59 and receptacles 60 and having dry layers similar to the layers 56 and 56^a may be used to complete the application of the labels to the bottles A and A' or the like, subsequent to the initial application thereof by the apparatus previously described herein. In such case the operative steps may be carried out in the following sequence:

An article such as for instance the bottle A', is first placed in the trough of the device of Fig. 8 in contact with the layer 56 to receive

moisture therefrom and is then placed in the apparatus of Figs. 5 and 6 and manipulated in the manner set forth hereinbefore to pick up a terminal label 23^a from the supply stack. The 5 bottle A' with the picked up label is then placed in the trough of a device such as shown in Fig. 8 but with a dry layer 56 to thereby complete the application of the label 23^a to said bottle A'; it will be obvious as the bottle A' with the initially applied label 23^a thereon is placed in the 10 trough of said device that the dry layer thereof will serve to wipe said label 23^a into firm and uniform adhesive contact with said bottle A'.

The further form of the novel apparatus illustrated in Figs. 10 to 13 inclusive, corresponds in 15 general construction and arrangement to those previously described, and differs therefrom only in details.

In the arrangement now being described, the 20 carriers 35 and upright members 37 with associated elements are replaced by another form of positioning means whereby the article to be labeled is located and guided in predetermined relation to the supply stack of labels 23. The 25 stack of labels is maintained in place on the table or top 17 by means of compressible guide members or pins 24 corresponding to the guide members or pins 24 of Figs. 1 and 2, and mounted and operating in exactly the same way.

30 The article positioning and guiding means, in the specific form illustrated, is designed to support and accommodate bottles A² of rectangular shape in cross-section, it being understood that this is illustrative only and not intended to define the limits of the particular positioning means. The latter consists of rods 61 slidably mounted in bosses 62 forming part of brackets 63 arranged in surface engagement with the lower face of the table 17 in registry with the longitudinal slots 20 thereof. The brackets 63 are connected by means of bolts 64 and nuts 65 with co-operating plates or slides 66 resting upon the shoulders 22 of the slots 20 and slidably fitting the latter; washers 67 are located on the bolts 45 64 in engagement with the lower surfaces of said brackets 63 to provide bearing surfaces for the associated nuts 65. To increase the range of adjustability of the rods 61 lengthwise of the slots 20 through which said rods 61 extend in upright relation to the top or table 17, the brackets 63 may be provided with slots 68 for the accommodation of the bolts 64 as shown in Fig. 11.

55 At their upper ends the rods 61 are provided respectively with holders 68 and 69 which, in the illustrated example, are designed to receive and support rectangular bottles A², it being understood that said holders 68 and 69 may be constructed also for accommodating bottles of different shapes and also other articles.

60 The holder 68 is in the form of a rectangular receptacle comprising an upright back and upper right side walls 70 and horizontal bottom lugs or members 71 as shown in Fig. 12; in the preferred arrangement a flat spring 72 is mounted upon the inner face of one of the side walls 70 for maintaining the bottle A² or equivalent article firmly in place in said holder 68. The holder 69 is in the form of an upwardly open or 65 U-shaped receptacle consisting of a horizontal bottom member and spaced upright legs or members 73; in the preferred form a flat spring 74 is mounted upon the inside of one of the upright legs 73 as shown in Fig. 13.

70 Preferably the holders 68 and 69 are con-

nected with the rods 61 so as to be readily disconnected therefrom at will, and for this purpose may be provided with internally threaded sleeves 75 for the threaded reception of the screwthreaded ends of said rods 61; lock nuts 76 5 may be provided for locking the holders 68 and 69 in position on the rods 61 against unintentional movement thereon. The rods 61 with the holders 68 and 69 are maintained and returned to their normally raised positions by means of 10 springs 77 which have one end in engagement with the base 15 and their other ends in contact with pins 78 carried by said rods 61 and serving in co-operation with the bosses 62 to also limit the upward movements of the rods 61 therein 15 under the influence of the springs 77. As shown in Fig. 11, the rods 61 may extend downwardly through the slots 32 of the base 15 so as to have the required range of movement necessary to the 20 operation of this form of the apparatus.

In practice, the supply stack of labels 23 is positioned upon the top or table 17 by the guide members or pins 24 in the same way as in the form of the apparatus shown in Figs. 1 and 2. By properly adjusting the brackets 63 and fixing 25 them in place by means of the bolts 64, nuts 65, and slides 66, the holders 68 and 69 are located so as to automatically present the bottle A² or equivalent article in predetermined relation to said stack of labels 23. 30

Assuming that the labels 23 are gummed upon their upper surfaces and are stacked with their gummed surfaces upward, a bottle A² is first moistened for instance by means of a device such as shown in Fig. 9, or in any other convenient manner, as by means of a suitable moistening pad. The moistened bottle A² is then placed in position on the positioning means by having its bottom end set into the holder 68 in engagement with the upright back thereof and 40 resting upon lugs 71. At the same time the neck of the bottle A² is placed in the holder 69 in resting engagement with the horizontal bottom thereof and with the conventional bead a² of said bottle A² in contact with the upright 45 legs 73 of said holder 69 as shown in Figs. 10 and 11; it will be understood that the holders 68 and 69 are located by adjustment of the brackets 63 so as to automatically provide the above 50 positioning of said bottle A² without special effort or care on the part of the operator. The springs 72 and 74 clamp the bottle A² in place in the holders 68 and 69 against unintentional transverse movement relatively thereto while the back of the holder 68 in co-operation with 55 the bottom of the bottle A², and the upright members 73 of the holder 69 in co-operation with the bead a² of said bottle A² fix the latter against longitudinal movement in one direction; the springs 72 and 74 in addition to their other 60 functions hold the bottle A² against unintentional lengthwise movement in the opposite direction. When the bottle A² is in place in the holders 68 and 69, said bottle A² preferably engages and rests upon the guide pins 24 as in 65 the form first described.

A downward pressure is now manually exerted on the bottle A² which depresses the holders 68 and 69 against the tension of the springs 77 and at the same time correspondingly depresses the 70 guide pins 24 against the tension of the springs 33 to thereby bring the moistened surface of the bottle A² into firm engagement with the gummed surface of the terminal label 23 currently at the top of the supply stack. In this 75

way said terminal label 23 is adhesively attached to the bottle A² and adheres thereto as the latter is removed from the apparatus. If necessary the application of said label 23 to said bottle A² may be completed in any conventional manner as by means of a device such as shown in Fig. 9 but having a dry layer 56a; it will be understood that with certain types of labels and articles the aforesaid supplemental steps will be unnecessary.

In any case, the operative cycle is repeated with successive bottles A² or their equivalent, and in each instance will result in the application of a label 23 thereto, each successive label occupying the same position on successive articles without any special attention on the part of the operator; all that the latter is required to do is to place the previously moistened bottle A² or its equivalent properly in place in the holders 68 and 69 and then to exert a downward pressure on said bottle A² to bring the latter or any other article into engagement with the current terminal label 23 of the supply stack after which the bottle A² or equivalent article with the applied label 23 adhering thereto may be removed from the apparatus.

The same procedure is followed if the labels 23 in the supply stack are not gummed with the exception that the bottle A² or other article instead of being moistened is first provided with a coating of adhesive applied to that part of the surface of said bottle A² or other article to which the label 23 is to be adhesively applied.

In all forms of the apparatus the stack of labels is located on a support at a predetermined point thereof, and the article to be labeled is positioned in predetermined relation to said stack and pressed into engagement with the terminal label thereof; the movements of the articles as pressure is applied thereto are controlled in predetermined relation to the supply stack so that the location of the labels on the articles is predetermined and all labels of a given group are uniformly applied to successive articles of a given group. In all of its forms the apparatus is reliable in performing its functions and requires no particular skill in its operation.

Various changes in the specific forms shown and described may be made within the scope of the claims without departing from the spirit of the invention.

I claim:

1. An apparatus for adhesively applying labels to articles comprising a support, brackets adjustably mounted on said support, guide members resiliently mounted on said brackets and adjustable therewith to different set positions to define an enclosure for maintaining a supply stack of labels in predetermined location on said support, said guide members adapted to be engaged by an article and to be shifted thereby as pressure is applied to said article to move the latter into engagement with the terminal label of said stack whereby said terminal label is adhesively attached to said article, and means whereby the movement of said article under pressure is controlled in predetermined relation to said stack to thereby definitely predetermine the location of said label on said article.

2. An apparatus for adhesively applying labels to articles comprising a support, brackets located on a surface of said support and including bosses, guide pins slidably mounted in said bosses and projecting in perpendicular relation to said support to predetermine the location of a supply

stack of labels thereon, springs effective on said guide pins to maintain the latter in normally raised positions to return said pins thereto, said guide pins adapted to be engaged by an article and to be depressed thereby as pressure is applied to move said article into engagement with the terminal label of said stack whereby said terminal label is adhesively attached to said article, and means whereby the movement of said article under pressure is controlled in predetermined relation to said stack to thereby definitely predetermine the location of said label on said article.

3. An apparatus for adhesively applying labels to articles comprising a support, a plurality of brackets adjustable in different directions on a surface of said support, bosses depending from said brackets, guide pins slidably mounted in said bosses and projecting in perpendicular relation to said support and adjustable with said brackets to different set positions to predetermine the location of a supply stack of labels on said support, means for securing said brackets against movement on said support to maintain said guide pins in a set position, springs effective on said guide pins for yieldingly supporting the same in normally raised positions in said bosses, said guide pins adapted to be engaged by an article and depressed thereby as pressure is applied to move said article into engagement with the terminal label of said stack whereby said terminal label is adhesively attached to said article, and means whereby the movement of said article under pressure is controlled in predetermined relation to said stack to thereby definitely predetermine the location of said label on said article.

4. An apparatus for adhesively applying labels to articles comprising a supporting table, means for definitely locating a supply stack of labels on said table, said means adapted to be engaged by an article and to be shifted thereby as pressure is applied to said article to move the latter into engagement with the terminal label of said stack whereby said terminal label is adhesively attached to said article, a pair of carriers adjustably mounted on a surface of said table, upright members carried by said carriers and having flat surfaces in spaced surface parallelism arranged to lie in surface engagement with said article, a second pair of carriers adjustably mounted on said surface of said table, and upright members carried by said last named carriers in convergent relation and having bevelled edges arranged to engage another portion of said article, said upright members co-operating with each other to control the movement of said article under pressure in predetermined relation to said stack to thereby definitely predetermine the location of said label on said article.

5. An apparatus for adhesively applying labels to articles comprising a supporting table, means for definitely locating a supply stack of labels on said table, said means adapted to be engaged by an article and to be shifted thereby as pressure is applied to said article to move the latter into engagement with the terminal label of said stack whereby said terminal label is adhesively attached to said article, a pair of holders movably mounted on said table and adapted to receive predetermined portions of said article and shiftable with said label locating means to control the movement of said article under pressure in predetermined relation to said stack to thereby

definitely predetermine the location of said label on said article.

6. An apparatus for adhesively applying labels to articles comprising a supporting table, means for definitely locating a supply stack of labels on said table, a pair of brackets adjustably mounted on said table, bosses depending from said brackets, spring-controlled rods slidably mounted in said bosses, and holders carried by said rods and 10 adapted to receive predetermined portions of said articles for maintaining the latter in predetermined relation to said stack of labels as said article is pressed into engagement with the terminal label of said stack to apply the same to 15 thereby predetermine the location of said label on said article.

7. An apparatus for adhesively applying labels to articles comprising a supporting table provided with a plurality of slots, brackets adjustably 20 mounted on the lower surface of said table in registry with some of said slots, slides mounted in said slots, fastening devices connecting said brackets with said slides, guide pins slidably mounted on said brackets and projecting upwardly 25 through said slots beyond said table to define an enclosure for a supply stack of labels thereon, springs for yieldingly maintaining said guide pins in their normal raised positions and for returning them thereto, a pair of carriers adjustably 30 mounted on the upper surface of said table, upright members carried by said carriers and having flat faces in spaced surface parallelism arranged to lie in surface engagement with said article, a second pair of carriers adjustably 35 mounted on the upper surface of said table, and upright members carried by said last named carriers in convergent relation and having bevelled edges arranged to engage another portion of said article, said upright members co-operating to 40 locate said article in predetermined relation to said supply stack and to maintain such relation throughout the label applying operation to thereby predetermine the location of said label on said article.

45 8. An apparatus for adhesively applying labels to articles comprising a supporting table provided with a plurality of slots, brackets adjustably mounted on the lower surface of said table, in registry with some of said slots, slides mounted 50 in said slots, fastening devices connecting said

brackets with said slides, spring-controlled guide pins slidably mounted on said brackets and projecting upwardly through said slots beyond said table, brackets adjustably mounted on the upper surface of said table in registry with others of 5 said slots, guide plates pivotally and resiliently connected with said last named brackets and co-operating with said guide pins to define an enclosure for a supply stack of labels on said table, means for securing said last named brackets in 10 adjusted positions, a pair of carriers adjustably mounted on the upper surface of said table, upright members carried by said carriers and having flat faces in spaced surface parallelism arranged to lie in surface engagement with said article, 15 a second pair of carriers adjustably mounted on the upper surface of said table, and upright members carried by said last named carriers in convergent relation and having bevelled edges arranged to engage another portion of said article, 20 said upright members co-operating to locate said article in predetermined relation to said supply stack and to maintain such relation throughout the label applying operation to thereby predetermine the location of said label on said article. 25

9. An apparatus for adhesively applying labels to articles comprising a supporting table provided with a plurality of slots, brackets adjustably mounted on the lower surface of said table in registry with some of said slots, slides mounted 30 in said slots, fastening devices connecting said brackets with said slides, guide pins slidably mounted on said brackets and projecting upwardly through said slots beyond said table to define an enclosure for a supply stack of labels 35 thereon, springs for yieldingly maintaining said guide pins in their normal raised positions and for returning them thereto, a pair of additional brackets adjustably mounted on the lower surface of said table in registry respectively with two 40 aligning slots, means for fixing said additional brackets in adjusted positions, spring controlled rods slidably mounted on said additional brackets and projecting upwardly through said slots beyond said table, and holders carried by said last 45 named rods for receiving predetermined portions of an article to position the same in predetermined label receiving relation to said supply stack of labels.

LOUIS MANDEL. 50
